No. 730,111.

Patented June 2, 1903.

UNITED STATES PATENT OFFICE.

AUGUST GRÄNTZDÖRFFER, OF MAGDEBURG, GERMANY.

PROCESS OF BOILING SUGAR SOLUTIONS.

SPECIFICATION forming part of Letters Patent No. 730,111, dated June 2, 1903.

Application filed February 2, 1903. Serial No. 141,496. (No specimens.)

To all whom it may concern:

Be it known that I, AUGUST GRÄNTZDÖRFFER, a subject of the Emperor of Germany, residing at Magdeburg, Prussia, Empire of Germany, have invented certain new and useful Improvements in the Process of Boiling Sugar Solutions, of which the following is a specification.

Carbonic acid has already been employed for assisting the crystallization of sugar in crystallizing apparatus. Now this invention has for its object a process for employing carbonic acid as a chemically-effective means in the boiling down of thick and thin fluids in vacuum or evaporating apparatus. The carbonic acid is introduced into the vacuum apparatus during the boiling down in any suitable manner as long as it is well distributed, the contents of the vacuum-pan being maintained at at least 78° centigrade, but preferably at from 79° to 81° centigrade. The carbonic acid must be heated previously to the same temperature. By this means the ammonia which is formed during the boiling and separates out, deteriorating the quality of the sugar, is converted into the easily-volatilized carbonate of ammonia.

As the use of carbonic acid allows of a

higher boiling temperature than is otherwise admissible, the separation of non-saccharine substances is avoided or diminished, and the more vigorous evaporation, which is supported by the escaping carbonate of ammonia, allows a portion of the non-saccharine substances to escape from the vacuum-pan.

35

The result of the process as established by the experiments was as follows: In the ordinary process the ash contents of the sugar was 1.35 per cent., and where the process hereinbefore described was employed it amounted to only .93 per cent.

35

I declare that what I claim is—
In processes for boiling down thick and thin liquids the introduction of carbonic acid into the juice, said carbonic acid being introduced at approximately the same temperature as that of the juice in the boiling-down pan, substantially as and for the purpose described.
